TOOTH BRUSH

Elhanan S. Chibnik, Mt. Vernon, N. Y.

Application May 12, 1937, Serial No. 142,108

2 Claims. (CL. 15—185)

My invention relates to brushes and more particularly to a tooth brush which can be collapsed into its handle.

One of the objects of my invention is to provide a tooth brush or other appliance having a handle which acts as a receptacle for the bristle portion when the same is not in use and wherein the said bristle portion is automatically presented in the operative position.

10 Another object of my invention is to provide such a tooth brush wherein the handle which operates as a latch to retain the bristle portion in the shielded and inoperative position can be manually compressed so as to release said bristle portion to the operative position.

15 Other objects of my invention will appear in the following description which represents a preferred embodiment thereof, it being understood that the objects above outlined are generally intended to explain the same without limiting it in any manner.

Fig. 1 is a side elevation of my tooth brush partly in section.

Fig. 2 is a similar view showing the tooth brush collapsed.

Fig. 3 is a section on the line 3—3 of Fig. 2.

Fig. 4 is a top view showing how the bristle portion is released.

Fig. 5 is a section on the line 5—5 of Fig. 1.

30 Fig. 6 is a perspective view of my tooth brush in the operative position.

In the drawing, 1 designates the handle of the tooth brush which is also the receptacle for the bristle portion 2, having the bristles 10 mounted therein. The handle 1 has a pin 3 secured to its walls and pivotally mounted on the shank of the pin 3 by means of the yoke 4 is the bristle portion 2. However, any hinge joint can be utilized to maintain these parts in 40 pivotal relation.

Within the recess of said yoke 4, I provide a spring 5 one of whose ends 6, bears against the bristle portion 2 and whose other end 7, bears against the handle 1. It is obvious therefore 45 that the spring 5 will normally maintain the tooth brush in the extended position. In order that this relation of the parts be not disturbed during the use of the tooth brush, the receptacle 1 is formed with projections 14 adapted 50 to engage the recesses 13 of the bristle portion when in the extended position. Since the parts are made of a resilient material, the projections 14 will engage the recesses 13 in a snap-fit.

The bristle portion 2 is provided with a groove 55 9 at its outer end and this is adapted to engage

a latch 8, formed on the end of the receptacle 1. When the bristle portion 2 is collapsed into the receptacle 1, the latch 8 will snap into the groove 9 and retain it against the action of the spring 5. The latch 8 is preferably formed integral with the receptacle 1 and is in the form of a projection thereon.

As heretofore explained the assemblage is made of a resilient material and the walls 11 of the receptacle 1 being of narrow width are 10 easily compressible. Referring particularly to Fig. 4, this shows the tooth brush in the collapsed position, and the fingers F compressing the walls 11 of the receptacle 1. This action elongates the receptacle 1 and the latch 8 leaves 15 the groove 9 releasing the bristle portion 2 which is then permitted to swing back to the dotted line position shown, impelled by the unhampered action of the spring 5.

I have shown a preferred embodiment of my 20 invention but it is obvious that numerous changes can be made without departing from its spirit. For example, while I have illustrated my invention as applied to a tooth brush, many other common articles may be formed so as to utilize 25 its principles. Also, I have shown the latch 8 in the receptacle engaging the groove 9 in the bristle portion but it is obvious that their positions might be reversed and it is understood that my invention covers this departure. This 30 variation is likewise applicable to projections 14 and the recesses 13.

I claim:

1. A collapsible tooth brush comprising a handle having resilient walls and having a recess 35 formed thereby, said walls being adapted to distort the shape of said recess when pressure is exerted on said walls, a bristle portion pivotally connected to said handle and adapted to fit into said recess when the tooth brush is collapsed, 40 spring means operating on said handle and bristle portion to maintain them in the extended position and latch means comprising complementary members on said handle and said bristle portion which engage to retain said bristle portion in 45 said recess against the action of said spring means, and which are caused to disengage when the shape of said recess is distorted.

2. A collapsible tooth brush comprising a handle having a recess formed therein, said 50 handle having resilient side walls and an end wall which are connected to each other by integral rounded edges, whereby pressure exerted on said side walls will cause said end wall to move outwardly, a bristle portion which is piv- 55

totally connected to said handle, spring means operating on said handle and bristle portion to maintain them in the extended position and complementary latch members carried by said end wall and said bristle portion which engage to retain said bristle portion in said recess against

the action of said spring means and which disengage when pressure is exerted on said side walls, said pressure causing the outward movement of said end wall which carries one of said latch members.
